DISPLAY SIGN INDICIA

Bernard Spangler, Philadelphia, Pa.

Application April 25, 1955, Serial No. 503,381

2 Claims. (Cl. 40—130)

The present invention relates generally to display signs and it relates more particularly to individual display-sign letters, numbers or other indicia.

An object of the present invention is to provide a novel construction for display-sign letters, numbers and other indicia, as well as a new and useful method of forming the same. Another object of the present invention is to provide novel display sign indicia which can be easily and inexpensively manufactured, with a minimum of hand operations and which are rugged, durable and capable of giving long service when used outdoors, even under the most adverse weather conditions.

Other objects and advantages of the present invention are apparent in the following detailed description, appended claims and accompanying drawings.

For the purpose of illustrating the invention, there is shown in the accompanying drawings one form thereof which is presently preferred and which has been found in practice to give satisfactory results; it being understood, however, that the present invention is not limited to the precise arrangements and instrumentalities illustrated.

Referring to the accompanying drawings in which like reference characters indicate like parts throughout:

Figure 1 is a perspective view of a display-sign letter forming one embodiment of the present invention.

Figure 2 is an exploded perspective view showing the main components of the embodiment of Fig. 1.

Figure 3 is a cross-sectional view taken generally along the line 3—3 of Fig. 1.

Figure 4 is an enlarged fragmentary cross-sectional view taken generally along the line 4—4 of Fig. 1.

In Figs. 1—4 I have shown a self-standing display sign letter, namely the letter "A" forming one embodiment of the present invention.

As best shown in Fig. 2, this embodiment is made up of the following main parts: a base or back 10 which is die-cast or otherwise suitably integrally formed of aluminum alloy or other suitable light-weight metal or the like; a reflector-member 12 of polished sheet-metal or the like adapted to fit within the back 10 in a manner to be hereinbelow described and carrying the lighting elements (such as fluorescent tubing bent into proper configuration); a front member or face 14 molded or otherwise integrally formed of light-transmitting (i.e. translucent or transparent) and preferably colored synthetic resin or the like, of a configuration matching that of the back 10; and lengths of molding strip 16 of generally F-shaped cross-sectional configuration, adapted to effect a detachable water-tight connection between the peripheral edges of the back 10 and the corresponding edges of the front or face 14.

As mentioned above, the back 10 is integrally formed of aluminum alloy or other appropriate metal by die-casting or other similar operation and includes a generally flat vertical back wall 18 having a forwardly-directed continuous peripheral flange 20. In the embodiment of Figs. 1 and 2, the back 10 is shaped into the

configuration of the letter "A" so that the continuous peripheral flange 20 includes a relatively small horizontal top portion 22, downwardly-diverging side portions 24, inwardly extending horizontal bottom portions or feet 26, relatively short upwardly converging inner portions 28 which are connected, at their upper ends, by an intermediate horizontal portion 30.

To complete the configuration of the letter "A" the back 10 is provided with an inner triangular flange 32 consisting of a base portion 34 and upwardly converging side portions 36.

Along the inside surfaces of the flanges 20 and 32, there are provided a plurality of spaced integrally formed lugs 38 which are adapted to receive self-tapping screws whereby the reflector 12 is mounted on the back 10 in the manner to be hereinbelow described.

The flanges 20 and 32 are also provided with a plurality of spaced holes 40 adjacent the forward free edges thereof, the holes being adapted to receive the fastening screws whereby the molding strip 16 can be secured to the flanges so as to lock the face 18 to the back 10 as will be hereinafter described.

The back wall 18 is provided with a pair of access openings 42 which permit servicing and/or replacement of transformer units 44 mounted within the back 10; removable water-tight cover plates 46 being provided for said openings 42.

Coming now to the reflector member 12, this element, as best shown in Fig. 2, is preferably integrally formed from relatively thin flat polished sheet metal stamped into the configuration of the letter "A" and of such size as to fit more or less snugly within the flanges of the back 10, as indicated in Fig. 4. A series of spaced peripheral openings 48 are provided in the reflector member 12; the openings 48 coinciding with the lugs 38. Self-tapping screws 50 are constructed and arranged to be inserted through the openings 48 and to make detachable engagement with the lugs 38, as best indicated in Fig. 4.

As shown in Figs. 2 and 3, appropriately bent fluorescent tubing 52 is mounted upon the polished front face of the sheet metal reflector 12 by means of spaced mounting posts 54. The ends of the tubing 52 are connected to the transformer units 44 through suitable openings in the reflector 12, as indicated in Fig. 3. As shown in Fig. 1, the transformer units are preferably secured to the inside of the side flange portions 24 of the back 10 by means of screws 56.

Instead of employing fluorescent tubing, I may use any other conventional source of illumination, as for example neon-filled tubing or incandescent tubing, individual spaced light bulbs, etc.

The bottom flange portions or feet 26 of the back 10 are preferably provided with a plurality of holes 58 whereby the assembled letter can be firmly mounted, in upright position, upon any appropriate horizontal surface S shown in Fig. 1.

The front member or face 14 is integrally formed of molded synthetic resin or the like which is light transmitting (i.e. translucent or transparent) and, preferably, is also colored. With a colored translucent plastic face 14, the light produced by the fluorescent tubing (or other source of illumination) is transmitted outwardly through the face in a more or less uniformly diffused manner so that the front of the letter appears to be evenly illuminated throughout.

The face 14 is integrally molded from a flat sheet of thermo-plastic synthetic resin in conventional manner, using appropriate molds, employing heating and pressure, in a manner well known in the art.

The face is molded to the suitable configuration of the letter "A" with a flat front wall 60 and rearwardly-di-

rected walls 62, 64, 66, 68 and 70 corresponding, respectively, to the peripheral flange portions 22, 24, 26, 28 and 30 of the back 10. The face 14 also has a rearwardly directed triangular wall 72 corresponding to the triangular flange 32 of the back 10; the triangular wall 72 defining the central opening of the "A."

A continuous outwardly-directed annular flange 74 extends around the walls 62, 64, 66, 68 and 70 and, as best indicated in Figs. 3 and 4, terminates in line with the outer peripheral flange portions of the back 10.

An inwardly-directed peripheral flange 76 is formed along the triangular center wall 72 and terminates in line with the triangular flange 32 of the back 10.

As mentioned above, the face 14 is connected to the back 10 by lengths of molding strip 16 which is F-shaped in cross-sectional configuration. Thus, as best shown in Fig. 4, the molding strip 16 (which is integrally formed of sheet metal or the like) includes a vertical arm 78 with parallel outer and inner flanges 80 and 82 formed at one end of the main arm 78. The parallel flanges 80 and 82 are spaced apart so as snugly to receive the peripheral flange 74 (or 76) of the face 14 therebetween. Angle irons 84 are used to connect the ends of the individual lengths of molding strip 16 at the corners of the letter; the ends of the flanges 80 and 82 being cut diagonally to provide snugly-fitting miter corners.

The main vertical arm 78 of the molding strip 16 is constructed and arranged to fit over the outside of the peripheral flange 20 (or the triangular flange 32) of the back 10, in a manner best shown in Fig. 4. The free edges of the flange 20 (or 32) bear against the molding strip flange 82 with an intervening gasket strip 86 providing a water-tight seal therebetween.

As shown in Fig. 2, the main arm 78 of the F-shaped molding strip 16 is provided with a plurality of holes corresponding to the holes 40 in the flange 20 (or 32) of the back 10. Self-tapping screws 90 are adapted to be inserted into the aligned holes so as to detachably connect the face 14 to the back 10 so as to complete the assembly of the display letter.

While I have described above a so-called free-standing letter (i.e. one which stands by itself resting upon and fastened to an underlying generally horizontal supporting surface), the present invention can also be embodied in letters and other sign indicia intended to be mounted in groups upon a single elongated back member or "fin" by means of screws or the like passing through appropriate holes (not shown) formed in the rear wall 18 of the back member 10, in a manner conventional in the art. This mounting of a number of letters or the like on a single "fin" is used especially with smaller-size letters.

With such smaller-size letters it may be desirable, in some cases, to eliminate the reflector member 12 and to mount the tubing or other source of illumination by securing the mounting posts 54 directly to the back wall 18 of the back 10, in an obvious manner. Also, in the case of smaller-size letters or the like, it may be more practical to mount the transformers 44 inside the "fin" or at some other place remote from the letters, instead of inside the back 10 as described above.

The use of an integral die-cast metal back and a molded synthetic resin face greatly cuts down on the cost and time of fabrication, as compared to conventional constructions heretofore employed and permits greater uniformity and interchangeability of parts. The use of integrally die-cast or molded constructions substantially increases the strength of the final letter or other advertising indicia

and ensures greater weather-tightness (thereby protecting the light source from deterioration or damage).

The present invention may be embodied in other specific forms and, therefore, the foregoing embodiments are to be considered in all respects as illustrative and not restrictive, reference being made to the appended claims as indicating the scope of this invention.

Having thus described my invention, I claim as new and desire to protect by Letters Patent the following:

- 10 1. A display-sign letter or the like comprising an integral back member of opaque lightweight metal or the like having a back wall and a relatively wide continuous forwardly directed peripheral flange; a separate metallic reflector member corresponding in shape to the back member and fitting snugly therewithin, means detachably securing the reflector member to the back member; a source of illumination mounted on the reflector member; a one-piece front member of light-transmitting synthetic resin or the like and corresponding in shape to the back member, said front member having a generally flat face and integrally formed rearwardly directed peripheral walls of lesser width than the back member flange and having an integral outwardly directed peripheral flange formed on the rearwardly directed walls with its free edges terminating adjacent the free edges of the peripheral flange of the back member; and separate means detachably connecting the peripheral walls of the front member to the free edges of the peripheral flange of the back member so as to form a water-tight seal therebetween comprising lengths of integral molding strip of relatively small F-shaped cross-sectional configuration, the parallel arms of the F receiving the outwardly directed peripheral flange of the front member while the base of the F overlies the peripheral flange of the back member for a short distance and is removably secured thereto; the inner free edge of the flange of the back member and the peripheral edge of the face of the reflector abut the inner of the parallel arms of the F with a sealing gasket disposed therebetween.
- 20 2. A construction according to claim 1 wherein the peripheral flange of the back member is provided with integrally formed lugs on its inner surface, said lugs underlying only a small portion of the edges of the reflector member, and wherein screws or the like extend through the reflector member and make engagement with the lugs, the lugs being recessed from the peripheral flange about the thickness of the reflector member to enable the face of the reflector member to be flush with the peripheral flange.
- 30 3. A construction according to claim 1 wherein the peripheral flange of the back member is provided with integrally formed lugs on its inner surface, said lugs underlying only a small portion of the edges of the reflector member, and wherein screws or the like extend through the reflector member and make engagement with the lugs, the lugs being recessed from the peripheral flange about the thickness of the reflector member to enable the face of the reflector member to be flush with the peripheral flange.
- 40 4. A construction according to claim 1 wherein the peripheral flange of the back member is provided with integrally formed lugs on its inner surface, said lugs underlying only a small portion of the edges of the reflector member, and wherein screws or the like extend through the reflector member and make engagement with the lugs, the lugs being recessed from the peripheral flange about the thickness of the reflector member to enable the face of the reflector member to be flush with the peripheral flange.
- 50 5. A construction according to claim 1 wherein the peripheral flange of the back member is provided with integrally formed lugs on its inner surface, said lugs underlying only a small portion of the edges of the reflector member, and wherein screws or the like extend through the reflector member and make engagement with the lugs, the lugs being recessed from the peripheral flange about the thickness of the reflector member to enable the face of the reflector member to be flush with the peripheral flange.
